UNITED STATES PATENT OFFICE.

WHEELER H. VIBBER, OF NEW LONDON, CONNECTICUT, ASSIGNOR OF ONE-HALF TO
THE GILLETTE-VIBBER CO., OF NEW LONDON, CONNECTICUT, A CORPORATION.

CONDUIT CAP.

Application filed April 10, 1924. Serial No. 705,573.

Fig. 1 is a view in side elevation showing my improved conduit-cap as applied to a junction-box, both being aligned upon a flat surface shown by broken lines.

Fig. 2 is a view of the cap and box in vertical central section, as applied to a clapboarded surface shown by broken lines.

Fig. 3 is a plan view thereof, with the hood and clamping-members removed.

Fig. 4 is a detached plan view of the one-piece bottom-plate and upstanding mounting-arm forming the bracket-member of my improved conduit-cap.

Fig. 5 is a broken view, in side elevation, showing a flat-topped junction-box, with the bracket-member of my improved conduit-cap mounted upon it.

Fig. 6 is a broken view in vertical central section of the bracket-member of my improved cap as applied directly to a conduit-pipe.

My invention relates to an improved conduit-cap, the object being to articulate its connection with a conduit-pipe or a junction-box mounted thereupon, so as to provide for variations in their line-up to conform to irregular surfaces, such, for instance, as the clapboarded or shingled side of a house.

With these ends in view, my invention consists in a conduit-cap characterized by its adaptation for articulated connection with a conduit-pipe or junction-box mounted thereupon, so that they may be installed out of line, as well as in line.

My invention further consists in a conduit-cap having certain details of construction and combinations of parts as will be hereinafter described and particularly pointed out in the claims.

In carrying out my invention, as shown in Figs. 1 to 4 inclusive, I employ a conduit-cap comprising a hood 10, a bracket-member consisting of a substantially horizontal bottom-plate 11 and a substantially vertical mounting-arm 12 made in one piece therewith, and two insulating gripping-members 13 and 14 having two gripping-faces and interposed between the spaced outer ends of the said hood and bottom-plate and secured in place by clamping-screws 15 passing through them and through the outer edge of the hood and the outer edge of the plate.

The mounting arm 12 is provided with holes 16 for the reception of a lag-screw or screws

17 by means of which it is secured to the surface to which the fixture is applied. Toward its inner end the bottom-plate 11 is shaped to form a transverse arch 18, the lower face of which substantially corresponds in curvature to the rounded top 19 of a junction-box 20, which may be of any approved construction. As shown, its rounded top is provided with a threaded bore 21, while its lower end or side is provided with a threaded bore 22 for the reception of a conduit-pipe 23. The bottom-plate of the cap is formed with an elongated clearance-opening 24 intersecting the arch 18 and, as shown, extending transversely across it. An externally-threaded thimble 25, having a polygonal head 26 to adapt it to be screwed home and removed by an ordinary wrench, is passed down through the said opening 24 into the threaded bore 21 of the junction-box 20 and when screwed home binds the conduit-cap thereto. Prior to this, the conduit-cap and junction-box may be rocked with respect to each other, as may be required, owing to the elongated character of the opening 24, which must be enough larger than the thimble to permit sufficient rocking movement between the cap and box to meet the requirements of practice.

Under the construction described, the cap and box may be arranged in line, as shown in Fig. 1, or out of line, as shown in Fig. 2, in which the mounting-arm 12 is canted with respect to the back of the junction-box to accommodate the clapboards 27.

In the modified construction shown by Fig. 5, the junction-box 28 is provided with a flat, instead of a curved, top, as is the junction-box 20.

In the modified construction shown by Fig. 6, my improved cap is shown as directly connected to the conduit-pipe 23 by means of the thimble 25, which is passed downward through the clearance-opening 24 of the bottom-plate 11 into the upper end of a conduit-coupling 29 screwed upon the upper end of the conduit 23 and virtually forming a part thereof. Under this construction, the arch 18 of the bottom-plate 11 engages with the projecting upper end of the coupling 29 on which it is rocked as required, prior to the turning home of the thimble 25.

I claim:

1. In a conduit-cap, the combination with a bracket having a mounting-arm by means

of which it is installed, and a substantially-
horizontal bottom-plate formed with an up-
wardly-set arch intersected by an opening,
of a thimble smaller in diameter than the
5 said opening in which it is located for the
articulated connection of the conduit-cap
with a complementary fixture, such as a con-
duit-pipe; of a hood covering the said plate,
conductor-clamping means located within
10 the hood and interposed between the same
and the plate, and means for securing the
said conductor-clamping means to the said
hood and plate.

2. In a conduit-cap, the combination with
15 a bracket having a mounting-arm by means
of which it is installed, and a substantially-
horizontal bottom-plate formed with an arch
intersected by an elongated clearance-
opening; of a junction-box, the upper end
20 of which has a threaded bore, a thimble pass-
ing downward through the said clearance-
opening which is larger than the said thimble
into the bore of the box, whereby the con-
duit-cap and box may be relatively adjusted,

25 a hood superimposed upon the said plate,
conductor-clamping means located within
the hood and interposed between the same
and the plate, and means for securing the
said conductor-clamping means to the said
30 hood and plate.

3. A conduit-cap having a bottom-plate,
the inner portion of which is arched and in-
tersected by a clearance-opening, a mounting-
arm made integral with the inner end of
the said plate, a hood, and clamping-mem-
bers interposed between the hood and plate;
35 in combination with a mounting-box having
its top rounded and formed with a threaded
bore, and an externally-threaded thimble
provided at its upper end with a flange, the
said thimble being passed downward through
40 the clearance-opening of the bottom-plate of
the cap into the threaded bore in the top of
the box, whereby the cap and box may be
installed in or out of line.

45 In testimony whereof, I have signed this
specification.

WHEELER H. VIBBER.
